LETTERING INSTRUMENT

Fred Howard Whiteley, Kansas City, Kans.

Application June 6, 1945, Serial No. 597,800

5 Claims. (Cl. 33—41)

1

This invention relates to lettering instruments of the character usually employed by draftsmen in setting down guide lines for the later production of a group of letters or figures, and has for its primary aim to provide a device of said character that is simple to operate, inexpensive to produce, accurate and convenient in its function, and adjustable to the desired size of letter.

This invention has for its further aim to provide a lettering instrument that has means thereon for indicating the distance between lines of lettering and for disclosing to the operator the space between a set of three lines that are to be employed as guides in producing the letters or numerals.

A further object of my invention is the provision of a lettering instrument having as a part thereof, a group of marking elements disposed in such fashion as to be in substantial alignment horizontally, when the movable portion of the instrument is at one end of its path of travel.

This invention has for other objects the provision of a lettering instrument capable of simultaneously drawing the required number of horizontal, spaced apart lines to be used as lettering guides; and susceptible of a large number of additional uses—all because of the character of structure chosen to embody the invention.

It has heretofore been customary to employ crude and inaccurate instruments for establishing guide lines for lettering, which instruments were objectionable because of inaccuracies and the absence of means for simultaneously drawing a group of lines, the distance between which were not governed by the devices per se.

In the drawing:

Fig. 1 is a top plan view of a lettering instrument made in accordance with the present invention.

Fig. 2 is an edge elevational view thereof.

Fig. 3 is an end elevational view of the instrument.

Fig. 4 is an inverted plan view of the lettering instrument.

Fig. 5 is an enlarged fragmentary cross sectional view taken on line V—V of Fig. 2, and looking in the direction of the arrows; and

Fig. 6 is an enlarged cross sectional view taken on line VI—VI of Fig. 1.

In the form of the invention chosen for illustration, the numeral 10 designates a body formed of light material, preferably transparent in character, and having a guiding edge 12 designed to

2

engage the straight edge of a T-square or the like, when the instrument is to be drawn across a sheet of paper mounted on a drawing board not here shown.

The salient 14 extending outwardly from the edge of body 10 opposite from guide edge 12, should be contoured substantially as illustrated to accomplish the desired end of positioning a group of marking elements, as shown in Fig. 4.

An arm 16 is pivotally mounted upon body 10 through the medium of structure clearly shown in Fig. 5. Body 10 is recessed as at 18 to receive the head portion of arm 16 and one edge of recess 18 is arcuate to conform to a similarly arched edge 20 on arm 16.

The arcuate edges of recess 18 and the head of arm 16 are concentric with the axis of rotation established on screw 22, which cooperates with thumb nut 24.

20 A pointer 26 is established on the free end of arm 16 for the purpose more fully hereinafter described. Also, arm 16 has a notch 28 to receive salient 14 when arm 16 is at the end of its path of travel in one direction around the axis of screw 22.

25 A pair of marking elements 30 and 32 respectively, are mounted on arm 16, one on each side of notch 28. These elements are on a radial line extending from the axis of screw 22 and 30 when the arm is in the position shown in Fig. 4, all marking elements and screw 22 are in substantial alignment.

35 A scale 34 cooperates with marker 36 in teaching the operator the position of elements 30 and 32. As these elements are swung around the axis of screw 22, the distance between lines 38 and 40 which marking elements 30 and 32 produce, becomes greater until the arm is moved to a position where elements 30 and 32 are on a vertical line or a line perpendicular to edge 12.

40 Marking element 15 will always remain stationary so far as arm 16 is concerned, and therefore, the line 42 which this marking element 14 produces, will be the base line of the lettering.

45 Regardless of the position of arm 16, therefore, the proper proportions will be maintained between lines 38, 40 and 42.

In the operation of the instrument and when a number of lines of lettering are to be produced, pointer 26 is employed as a guide and the last or lowermost line 42 of the set of lines just made, is utilized by registering pointer 26 therewith. When this is done, guide edge 12 is placed against the straight edge of a T-square, for example, and the instrument drawn in the direc-

tion of the arrow shown in Fig. 1. Thus, a spacing instrument as well as means for producing guide lines for lettering, is available.

Straight edge 44 on arm 16 is usable as means for drawing lines at the desired angle with respect to edge 12, and under such conditions, the scale 46 is brought into play.

The marking elements are each formed as shown in Fig. 6, and comprises a tubular standard 48, a head 50 and a screw-threaded shank 52 on said head to enter the bore of standard 48. A marking lead 54 is frictionally gripped by standard 48 and projects therefrom to a point where the end will engage the paper on the drawing board.

Standard 48 is shouldered as at 56 and a shoulder 58 on body 10 or arm 16, as the case may be, serves as a purchase for a spring 60 held under tension by nut 62. Thus, the marking element assemblies may be removed from their operative position and the marking lead 54 may be fed as fast as used.

It is understood that lettering instruments having physical characteristics different from those illustrated and described, might be made without departing from the spirit of the invention or scope of the appended claims.

Having thus described the invention, what is claimed as new and desired to be secured by Letters Patent is:

1. A lettering instrument of the type described, comprising a body having a guiding edge; an arm pivotally mounted on the body; and a plurality of marking elements, certain of the elements being on the body and the remaining elements being on the arm, the marking elements and the pivotal connections between the body and arm being in substantial alignment on a line parallel with and spaced from the said guiding edge when the arm is at one end of its path of movement about the pivotal connection.

20

25

30

35

40

2. A lettering instrument of the type described, comprising a body having a guiding edge; an arm pivotally mounted on the body; and a plurality of marking elements, certain of the elements being on the body and the remaining elements being on the arm, the marking elements and the pivotal connections between the body and arm being in substantial alignment on a line parallel with and spaced from the said guiding edge when the arm is at one end of its path of movement about the pivotal connection, said arm having a pointer thereon at the free end thereof and serving as an indicator for the positioning of the instrument when guide lines for more than one row of lettering are to be established.

3. A lettering instrument of the type described, comprising a body having a guiding edge; an arm pivotally mounted on the body; a pair of spaced apart marking elements on the arm; and a single marking element on the body, said body and arm being formed and so supporting the elements as to have the marking element on the body between the pair of marking elements on the arm when the arm is at one end of its path of travel about the pivotal connection.

4. A lettering instrument of the type described, comprising a body having a guiding edge and an outwardly projecting salient at the opposite edge thereof; an arm pivotally mounted on the body and having a notch formed thereon to receive the salient; a marking element carried by the salient; and a marking element on each side respectively of the notch whereby the marking elements are substantially in alignment when the salient is within the notch.

5. A lettering instrument of the character set forth in claim 4, wherein the substantially aligned marking elements are on a radial line extending from the pivotal mounting of the arm.

FRED HOWARD WHITELEY.
